WATCH BRACELET

Rudolph Bohnenberger, New York, N. Y.

Application January 15, 1952, Serial No. 18,080

Term of patent 14 years

(Cl. D45—4)

To all whom it may concern:

Be it known that I, Rudolph Bohnenberger, a citizen of the United States, residing at New York, in the county of New York and State of New York, have invented a new, original, and ornamental Design for a Watch Bracelet, of which the following is a specification, reference being had to the accompanying drawing, forming part thereof.

In the drawing:

Fig. 1 is a top plan view of a watch bracelet, showing my new design;

Fig. 2 is a side elevational view of the same;

Fig. 3 is an enlarged fragmentary view showing a portion of Fig. 2; and

Fig. 4 is a similar view to Fig. 3 showing the bracelet portion in partially curved position.

I claim:

The ornamental design for a watch bracelet, as shown.

RUDOLPH BOHNENBERGER.
